UNITED STATES PATENT OFFICE.

HOWARD C. SYLVESTER, OF BAKERSFIELD, CALIFORNIA.

SWITCHMAN'S LANTERN.

Application filed August 24, 1925. Serial No. 52,117.

My invention relates to improvements in lanterns such as those used by switchmen, and my object is to provide a generally improved and simplified lantern of this type which, although being rather inexpensive, is exceptionally rigid, efficient and desirable.

With the foregoing in view, the invention resides in the novel subject matter herein-after described and claimed, the description 10 being supplemented by the accompanying drawings.

Figure 1 is a vertical sectional view of a lantern constructed in accordance with my invention.

Figure 2 is a horizontal sectional view as indicated by line 2—2 of Fig. 1.

Figure 3 is a perspective view of the frame structure and base.

Figure 4 is a side elevation of the burner-20 carrying oil pot removed from the remainder of the lantern.

In the drawings above briefly described, the numeral 1 designates an annular base wall whose upper end receives the lower end 25 of a globe 2, said wall being formed near its upper end with air inlet perforations 3, while at its lower end, said wall is provided with internal screw threads 4 which are preferably formed on a separate piece of metal soldered or otherwise secured to the metal of which the wall 1 is formed. A plurality of arched wires 5 have their lower ends suitably secured at 6 to the upper portion 30 of the wall 1, said arched wires having horizontally disposed crown bars 7 which are located on a circular line and contact with a radially split top ring 8. This ring is secured upon the crown bars 7, preferably by wire wrappings 9 and solder, and the ends 10 of the ring are disposed in horizontally spaced relation upon one of said crown bars. The portion of this bar, between the ends 10, is surrounded by a sleeve 11 which is carried by a base flange 12 of a lantern top or cap 13, said sleeve and the contained crown bar forming a very unique, rigid and effective hinge for connecting the cap or the like 13 with the frame structure of the lantern. Any suitable latch 12^a may be employed to engage the ring 8 and hold the cap or the like 13 in its proper operative relation with the other parts of the device.

The vertical leg portions of the arched wires 5 are preferably secured to a wire ring 14 which not only braces them, but

assists in guarding the glass globe 2. Secured to two of these leg portions, at diametrically opposite points, are the lower ends 15 of an arched one-piece wire handle 16, the securing being preferably accomplished by wire wrappings 17 and solder, so that a rigid, permanent connection is provided between the handle and the frame. The greater portion of the handle 16 is received in a yieldable tube 18, such as a length of hose, 60 and the ends of this tube 18 are held in the open upper ends of a pair of vertically elongated, downwardly tapered, metal sleeves 19 which surround the leg portions 20 of the handle and are soldered or otherwise secured thereto at their lower ends, as indicated at 21. By employing the construction disclosed, in the formation of the handle and in attaching it to the frame of the lantern, the latter may be much more readily handled than when other forms of carrying handles are used.

The cap 13, above briefly mentioned, includes a vertical, annular side wall 22 whose upper portion is perforated as at 23, and a metal cap 24 is secured to the upper edge of this wall. Within the confines of the wall 22 and below the perforation 23, is a horizontal circular plate 25 having a downwardly extending annular flange 26 which engages the upper end of the globe 2. The plate 25 is formed with vent openings 27, and with outwardly inclined baffles 28 at the inner edges of these openings, portions of said plate being preferably stamped upwardly to simultaneously form said openings 27 and baffles 28. A stem 29 is rigidly secured to the cap 24 and projects downwardly therefrom through an opening 30 in the plate 25, and a nut 31 is threaded on said stem, under said plate, to limit the downward movement of the latter under the influence of a coiled spring 32, when the cap 13 is opened to remove the globe 2. When the cap is closed, the flange 26 engages the globe and the spring 32 is compressed to retain said flange in tight contact with said globe.

The cap construction just described is very advantageous, as it not only permits proper burning of the lantern when in use, but when said cap is swung open and the nut 31 is removed, all internal parts of the cap may readily be removed for cleaning, furthermore by threading the stem 29 and

providing the nut 31 the plate 25 and its flange 26 may be lowered or adjusted to engage short globes.

The burner B may be of any desired construction, and it is carried by the top 33 of a fuel pot 34. This pot is provided with an annular side wall whose lower portion 35 is outwardly offset from its upper portion 36 to provide an external ledge 37 and also to enlarge the lower portion of said pot, so that it will contain an unusually large quantity of fuel. A continuous vertical flange 38 rises from the outer edge of the ledge 37 and forms with the latter a drip collecting trough or gutter, and around the lower portion of the pot 34, screw threads 39 are provided to engage the threads 4. The pot is provided with an outstanding base flange 40 which not only constitutes a base for the entire lantern, but forms a hand grip for use when removing the entire fuel pot from the remainder of the lantern, or when re-applying this unit of the device. It will be seen that any oil or other fuel running down the sides of the pot, from the burner B will be caught in the trough 37-38, and each time the fuel pot is removed for refilling or wick trimming, this trough may be easily cleaned. Thus, there is no danger of any oil finding its way to the outer side of the lantern, causing dust to accumulate and giving an unsightly appearance.

In the preferred form of construction, the base flange 40 is formed by the peripheral portion of a base plate 41, and the body portion of this plate forms the bottom for the oil pot 34. The lower portion 35 of the pot wall and the flange 38 may well be formed from a continuous wall of sheet metal, and the upper portion 36 is preferably in the form of a smaller wall with its lower end bent outwardly to provide the ledge 37, the latter being soldered or otherwise secured to the wall 35. Also, the threads 39 are preferably provided upon a separate sheet metal ring and the latter suitably secured to the wall 35.

It will be seen from the foregoing that I have provided a simple and inexpensive switchman's lantern, yet one which is efficient and very desirable, and as excellent results have been obtained from the construction shown, it is preferably followed. However, within the scope of the invention as claimed, modifications may be made.

I claim:

1. A lantern comprising a globe-containing frame having a circular wall at its upper end and a cap secured to said wall, a horizontal plate within the confines of said wall and having a downwardly projecting globe holding flange, the portion of the wall above said plate being perforated, said plate

having a plurality of heat escape openings 65 spaced around its center and being provided at the inner edges of said openings with outwardly inclined baffles, a threaded stem projecting rigidly downward from the center of the aforesaid cap and passing 70 through an opening in said plate, a spring for urging said plate downwardly, and a nut threaded removably on said stem under said plate to permit the same to be lowered and to limit its downward movement when the 75 globe is removed from the lantern.

2. A lantern comprising a globe-containing frame having an annular wall at its lower end provided with internal screw threads, and a burner-carrying fuel pot having a drip collecting gutter around its lower portion and integral an outstanding base flange, the major portion of said pot and the gutter of the latter being within the confines of the aforesaid wall, said pot being 80 provided with external screw threads removably engaged with the threads of said wall, the base flange of said pot forming a base for the entire lantern and constituting 85 a hand grip for unthreading the pot from the wall.

3. A lantern oil pot having an annular side wall whose lower portion is outwardly offset from its upper portion to increase the capacity of the lower portion of the pot and to form an external ledge, and an annular flange rising from the outer edge of said ledge to form therewith a drip collecting trough.

4. A lantern oil pot comprising a base plate, an annular wall rising therefrom and having a liquid-tight connection therewith, a smaller annular wall spaced inwardly from the upper portion of the first named wall and spaced upwardly from said base plate, the lower end of said smaller wall having an outstanding annular flange secured to the first named wall below the upper edge of the latter, and a burner-carrying top plate secured to said smaller wall.

5. A lantern comprising a base, a plurality of arched wires secured at their lower ends to said base and having horizontal longitudinally curved crown bars disposed on a circular line, a radially split top ring secured to said crown bars and having its ends spaced apart upon one of said crown bars, a top member having a hinge sleeve surrounding said one crown bar between the ends of said split top ring, a latch for detachably connecting said top member with the ring, and an arched handle connected at its ends to diametrically opposed leg portions of said arched wires.

In testimony whereof I have hereunto affixed my signature.

HOWARD C. SYLVESTER,
